EXPANDER

Harry J. Detwiler, Pueblo, Colo.

Application December 11, 1934, Serial No. 757,020

8 Claims. (Cl. 309—12)

The invention relates to an expander and more especially to an adjustable expander for pistons of the slotted type employed in automobiles or other industrial engines.

5 The primary object of the invention is the provision of an expander of this character, wherein the same is readily applicable to the skirt of a piston of the slotted type for the expanding of the latter, the expander being readily adjustable, 10 flexible and double acting, and such expander may be employed as a cushion or shock absorber between two moving parts or for the flexing action therebetween.

Another object of the invention is the provision 15 of an expander of this character, wherein the same includes an expanding clip having tips for engagement with the opposite parts or portions of moving parts, particularly the skirt of the slotted type piston, and such clip can be tensioned or expanded for flexing thereof and the 20 expanding action inherent thereto, the clip being susceptible of a wide range of adjustment and positive in action.

A further object of the invention is the provision 25 of an expander of this character, which is extremely simple in its construction, thoroughly reliable and effective for the purposes intended thereof, readily and easily adjustable, susceptible of being held in its adjusted position against 30 accidental disturbances, strong, double acting, durable, readily and easily applied for use and removed after its use, and inexpensive to manufacture and install.

With these and other objects in view, the invention 35 consists in the features of construction, combination and arrangement of parts as will be hereinafter more fully described in detail, illustrated in the accompanying drawing, which discloses the preferred embodiment of the invention, 40 and pointed out in the claims hereunto appended.

In the accompanying drawing:

Figure 1 is a vertical longitudinal sectional view 45 through a slotted piston showing the expander constructed in accordance with the invention applied to the skirt of the piston.

Figure 2 is a sectional view on the line 2—2 of Figure 1 looking in the direction of the arrows.

Figure 3 is a view similar to Figure 2 showing the expander in side elevation.

50 Figure 4 is a sectional view on the line 4—4 of Figure 1 looking in the direction of the arrows.

Figure 5 is a sectional view on the line 5—5 of Figure 1 looking in the direction of the arrows.

55 Figure 6 is a sectional view on the line 6—6 of Figure 1 looking in the direction of the arrows.

Figure 7 is a perspective view of the expanding clip.

Figure 8 is an exploded perspective view of the adjusting screw for the expander and an adjunct thereto.

Similar reference characters indicate corresponding parts throughout the several views in the drawing.

Referring to the drawing in detail, A designates generally a portion of a piston having its skirt B provided with the split or slot 10 so that the skirt can be expanded for tight fitting within a cylinder. Adapted to be applied to the skirt B of the piston A is the expander constituting the present invention and hereinafter fully described.

The expander comprises a spring clip, preferably made from a single length of springy wire of the proper gage for strength and durability, and has the tensioning arms 11, these having the reversely outwardly converging portions 12 and 13, the latter carrying the loops 14 provided with attaching prongs or tips 15 which are disposed in divergent relation to each other for engagement in holes 16 provided in the skirt B at opposite sides of the slot 10 and in this fashion the clip is mounted in working relation to said skirt for the expanding of the same.

Engaged in the loops 14 are the wings 17 of an adjustable nut 18 threaded on an adjusting screw 19, its head 20 being provided with a screw driver slot 21 for convenience in adjustment of the screw 19. The screw 19 has swiveled thereon an expanding wedge in the form of a circular tapered head 22 which is located between the loops 14 of the clip and operates under wedging action therebetween for the expanding of the clip which when mounted by the engaging of the tips 15 in the holes 16 in the skirt B results in the expanding of the skirt B of the piston A, as will be obvious.

The head 20 of the screw 19 accommodates a cotter pin 23 which prevents the accidental turning of the screw 19 on adjustment thereof.

In the use of the expander the nut 18 is assembled with the clip and by spreading its arms 11 the wings 17 of said nut 18 can be engaged in the loops 14 of the clip and this nut 18 carries the adjusting screw 19, its end next to the head 22 being swiveled in a socket 24 provided in the underside of said head and this head when swiveled on the screw plays between the converging loops 14 carried by the arms 11, so that by adjustment of the screw 19 the clip can be expanded or spread for the expanding of the skirt

B when the expander is attached thereto, as exhibited in Figures 1 to 6 of the drawing.

It should be apparent that this expander can be utilized as a shock absorber or as a variable 5 adjustable cushion for opposed moving parts when engaged therewith, in addition to service as an expander, in that the arms 11 will be placed under tension by the head 22 on adjustment thereof, the clip being inherently resilient and 10 flexible.

The expander is double strength and twin acting as expanding strength lies in the two arms 11 and these arms can be spread apart under 15 adjustment of the head 22 in the use of the device.

What is claimed is:

1. A device of the character described comprising a clip having inherently resilient spreading arms carrying loops, a nut seated in the loops 20 and between the same, an adjusting screw engaged with the nut, and an expanding means swiveled with the screw and active upon the loops for spreading action upon the same.

2. A device of the character described comprising 25 a clip having inherently resilient spreading arms carrying loops, a nut seated in the loops and between the same, an adjusting screw engaged with the nut, an expanding means swiveled with the screw and active upon the loops for 30 spreading action upon the same, and anchoring tips on said loops for attachment of the clip with opposed parts or separated portions of a part.

3. A device of the character described comprising 35 a clip having inherently resilient spreading arms carrying loops, a nut seated in the loops and between the same, an adjusting screw engaged with the nut, an expanding means swiveled with the screw and active upon the loops for spreading action upon the same, anchoring tips 40 on said loops for attachment of the clip with opposed parts or separated portions of a part, and means engaged with the screw to prevent accidental displacement thereof after adjustment of the same.

4. In combination with a piston having a skirt

with a longitudinal slot and a pair of openings one on each side thereof, an expander comprising a resilient element formed from a single strand of resilient material bent over upon itself to provide an arcuate bight merging into a pair of legs 5 substantially perpendicular to the plane of the bight and merging into extensions converging upwardly toward each other which in turn merge into extensions downwardly disposed in substantial parallelism with the first mentioned extensions and terminating in lugs at substantial right angles thereto passing by the outer side of the legs and having the terminals disposed in the openings, and means cooperable with the extensions to cause the expansion of the skirt.

5. A device of the character described comprising a clip having inherently resilient spreading arms carrying loops, means seated in the loops and between the same for expanding of said loops with relation to each other and means supported by the loops and adjustable for rendering active the first-named means.

6. A device of the character described comprising a clip having inherently resilient spreading arms carrying loops, means seated in the loops and between the same for expanding of said loops with relation to each other, means supported by the loops and adjustable for rendering active the first-named means and anchoring means on said loops for attachment of the clip with opposed parts or separated portions of a part.

7. A device of the character described comprising a clip having inherently resilient spreading arms carrying loops and adjustable means seated in the loops and between the same for the spreading action of said loops relative to each other.

8. A piston skirt expander comprising a resilient body portion, a pair of resilient arms extending from one end of said body portion, the ends of said arms being adapted to be secured to a piston skirt, and tensioning means associated with and movable longitudinally of said body portion intermediate said arms.
